UNITED STATES PATENT OFFICE.

GEORGE N. MESERVE, OF BOSTON, MASSACHUSETTS.

FORM FOR CONCRETE STRUCTURES.

1,119,712.

Specification of Letters Patent.

Patented Dec. 1, 1914.

Application filed July 21, 1911. Serial No. 639,751.

To all whom it may concern:

Be it known that I, GEORGE N. MESERVE, of Boston, in the county of Suffolk and State of Massachusetts, a citizen of the 5 United States, have invented a new and useful Improvement in Forms for Concrete Structures, of which the following is a full, clear, and exact description, reference being had to the accompanying drawings, forming 10 a part of this specification, in explaining its nature.

My invention relates to that type of sectional form which consists of a series of parts or units assembled to form a wall presenting a facing against which cement is laid and allowed to harden after which the form is disassembled leaving the concrete structure intact. Usually the form consists of 15 adjacent spaced walls between which the 20 cement is run or laid.

The objects of my invention are several; among them is to provide units consisting of relatively right, thin metal plates that can easily be handled and admit of repeated 25 use without undue wear, and essentially plates made to possess as nearly absolute inflexibility as possible for if flexibility reside in the unitary plates it is practically impossible to eliminate such from the complete 30 form. The importance of this can be better appreciated when it is realized that whatever imperfection may exist in the form by reason of undue flexibility of its parts such imperfection is reflected in the molded 35 structure.

Another object of my invention is to provide an improved means for combining the unitary plates, or, in other words, for securing them to one another. It is of course 40 necessary that the plates be so combined as to present a smooth, continuous bearing face, which means that they must be combined with practically absolute precision. A skilled workman might accomplish this, but 45 it is my object to provide such means that the units or plates may be properly combined by unskilled labor, that is, by providing such means of fastening that the combination of the plates resolves itself into a purely 50 mechanical operation in which experience or judgment plays no part.

It is a further object of my invention to provide an improved means for obtaining the spaced retention of the units or plates 55 when combined and essentially one that can be removed from the molded concrete struc-

ture without disfiguring it when the form is disassembled.

The construction in which the several objects of my invention are embodied and the 60 various details of construction to which it otherwise relates can best be seen and understood by reference to the drawings, in which—

Figure 1 shows the combined units or 65 plates and means for combining the same in front elevation. Fig. 2 shows in plan a portion of the angle-bars by which each plate is reinforced as will be explained. Fig. 3 is a side elevation of a portion of one of the 70 units or plates together with the angle-bars secured thereto and the fastening for combining the same. Fig. 4 is a section on the line 4—4 of Fig. 3. Fig. 5 is a section on the line 5—5 of Fig. 3. Fig. 6 is a section 75 on the line 6—6 of Fig. 1. Fig. 7 is a side elevation of a portion of one of the connecting bars of the form to which reference will hereinafter be made. Figs. 8 and 80 9 are side elevations of the fastenings for these bars, showing the relative changed positions of these fastenings. Fig. 10 is a view mainly in plan of a portion of said bar and fastening coöperating therewith together with a portion of one of the space blocks to 85 which reference will hereinafter be made, and Figs. 11 and 12 show mainly in side elevation different adjusted positions of the fastening device shown in Fig. 3 together with portions of the plates or units and 90 angle-bars affixed thereto with which the bars are adapted to coöperate.

Referring to the drawings:—1 represents the units or plates of which the form is made or built up. These units are preferably 95 made of galvanized sheet steel of any suitable size and form depending upon the work to be done. In ordinary practice each unit is made of 20 gage sheet steel and about two feet square. Each of the units or plates is 100 reinforced or stiffened in the following manner: Running around the back of each plate adjacent its edges is an angle-bar 2. This angle-bar is right-angular in cross section having two flanges 3 and 4, respectively. 105 Of these flanges the flange 3 is affixed to the plate, being preferably riveted thereto, while the flange 4 projects outwardly at right angles from the edge of the plate. The angle-bar is continuous, that is, it runs 110 around the entire edge of the plate and its ends are fastened together in any suitable

manner as by an angular piece 5 riveted thereto. The location of the angle-bar is also such that the outer side or face of its flange 4 which projects from the plate will 5 be just flush with the edges of the plate. Each plate is further reinforced by crossed braces 6 which run diagonally across the back of the plate to engage the diagonally opposite corners of the angle-bar secured 10 to it and at which points the ends of the braces are turned in opposite directions to extend for some little distance along the flanges 4 of the iron bar and to which the turned ends of the braces are secured, pref- 15 erably by riveting. These braces act not only to strengthen and reinforce the plate itself and prevent lateral and torsional bending, but also afford very material assistance to the angle-bar, in other words, 20 forming therewith an exceedingly stiff frame or backing for each of the respective plates.

The assembling of the units or plates is accomplished by securing the plates edge-wise to one another in the following manner: The flanges 4 of the angle-bars adjacent all four edges of the respective plates are each provided with spaced slots 7 (see Fig. 2). These slots are carefully made and occupy the same relative positions in the re- 25 spective flanges of the angle-bars for all the plates so that when the plates are combined by bringing their edges together the flanges 4 of the angle-bars adjacent these edges will also be brought together to abut one another 30 and the slots 7 therein will coincide.

Attached to each of the flanges 3 of the angle-bars on all four sides of the respective plates and just adjacent one of the slots 7 therein are fastenings 8. Each of these fas- 40 tenings has a base plate 9 riveted or otherwise fixedly secured to the flange 3 of the angle-bar. Pivotal secured to the base plate 9 by a pin 10 is a clamping member 11 having a body 12 and jaw 13 carried by 45 the body. Each of the clamping members 11 is arranged and operated to have a pivotal action with relation to the pin 10 by which the member may be turned so that the jaw 13 thereof will pass through the 50 slots 7 of abutting flanges 4 of adjacent plates and the edge 15 of the jaw encounter the inner ends 14 of these slots. Each of the clamping members is also arranged and op- 55 erated to then have a drawing movement relative to the pin 10 by which the portion or edge 16 of the jaw is made to draw in against the abutting flange of the plate ad- 60 jacent that to which the member is secured, the jaw then acting to bind the two flanges and plates securely together, and in which position the jaw is positively retained until released.

For operating the clamping member 11 there is provided a lever 17 having an oper- 65 ating arm 18 and a power arm or head 19.

The lever is pivotally secured to the base plate 9 by the pin 10 which passes through the clamping member 11 and with relation to which said member has movement as aforesaid. The lever is also so arranged 70 that its power arm or head will lie outside and adjacent the body 12 of the clamping member to frictionally engage the same by which this member and the head of the lever will turn together as the lever is pivotally 75 turned. The power arm or head of the lever is itself in the nature of a plate so as to present a large friction-bearing surface against the clamping member so that these parts will readily turn together as the lever is 80 turned.

Projecting from the body 12 of the clamp- 85 ing member is a pin 20 which extends through a slot 21 in the head of the lever. The disposition and arrangement of this pin and slot are such that when the clamp- 90 ing member has been turned by the lever to a certain position and the clamping member held against further turning, then as the lever is further turned its head will draw 95 over the pin 20 by the sides of the slot 21 therein and thereby act to move or draw the clamping member toward the pin 10 or in a reverse direction depending upon the direc- 100 tion in which the lever is turned. This drawing movement of the clamping member is possible by reason of a slot 22 formed in the body of the member through which the pin 10 extends. The clamping member is accordingly capable of drawing by or over 105 the pin 10 and is guided during such move- 110 ment by it. The fastening is also such that after the lever has drawn in the clamping member this member cannot be turned back or pivotally reversed by the turning of the lever until by a reverse movement of the lever the clamping member has been moved out to its normal position when a reverse pivotal movement of the clamping member and jaw carried by it is effected as the lever 115 is further reversely turned. This is ac- 120 complished by affixing to the base plate 9 a pin 23 which works within an angular slot 24 formed in the body of the clamping mem- 125 ber. The disposition and arrangement of this pin and slot are such that the portion 130 of the slot will permit such pivotal turning of the clamping member by the lever as may be necessary, the pin 23 simply running in this portion of the slot as the clamping member is turned. When, however, the clamping member has been turned to a posi- 130 tion where the inward drawing action is started, then the clamping member becomes so moved that the pin 23 will enter a por- 135 tion 26 of the slot 24 and thereby prevent a reverse turning of the clamping member until the pin 23 has been released from this portion of the slot, obtained by moving the clamping member outwardly to its normal

position which is accomplished by the lever as above explained.

The essential capability of the above described means of fastening resides not only in a function of securely affixing the plates to one another but also in a function of drawing the plates into proper aligned or connecting position relatively to one another when fastening is made.

It has already been explained that when the abutted plates are in their proper positions the fasteners along the abutting edges of adjacent plates will be brought into line and the slots 7 in these flanges will be aligned. The fastenings act to bring the plates and flanges into proper positions by effecting a proper coincidence between the slots of adjacent flanges through which the jaws of the respective fastenings are adapted to pass. The proper projection or transverse positioning of the plates is accordingly accomplished by making the jaws 13 of the fastenings of substantially the same width as the slots through which they extend so that the easy passing of the jaws through the slots of adjacent plates is sufficient to draw the plates into proper alignment as regards their projection. In order that the jaws 13 may easily enter the slots, the slots 30 may be made wider than the jaws at the point of entry but gradually narrowing toward their inner ends 14 where the width of the slots is substantially the same as that of the jaws. The preferred form of the 35 slot 7 is most clearly shown in Fig. 2, wherein it will be seen that the wide ends of the slots are formed with inclined edges the inner ends of which merge into the narrow portions of the slots and the outer ends 40 of which diverge to form enlargements. These inclined edges constitute cam surfaces which co-operate with the jaws 13, so that when a jaw 13 is introduced into the enlargements or wide portions of the slots 7 of 45 two adjacent plates not in exact transverse alignment, and the fastening tightened, engagement of said jaw with the corresponding cam surfaces, as it moves into the narrow portions of the slots, serves to draw 50 said plates into their proper transverse position.

The sideways extension or longitudinal positioning of the plates both longitudinally and vertically is effected by the fastenings in a little different manner. Each fastening is so made that when the jaw of the fastening is turned through the slot in the angle-bar to which the fastening is secured it will be caused to bring its edge 15 with respect to the inner end 14 of the slot 7 which it is passing to a different position. The inner edge 14 of the slot will then extend at right angles to the slot, but in a position which is as the inner edge of the slot 7, and which is the jaw is of sufficient length to extend

through the slots of abutting angle-bars of adjacent plates the inner edge 15 of the jaw will accordingly be brought into engagement with the inner end 14 of the slot in the adjacent bar and will therefore tend, 70 when the ends 14 of the two slots are out of line, to bring them into proper alignment. Inasmuch as there are always two fastenings for securing together the abutting angle-bars on all sides of the respective plates, 75 the ends inasmuch as the jaws of these fastenings are turned in reverse or opposite directions to engage the inner ends 14 of the respective sets of slots they will accordingly tend to bring the inner ends 14 of both sets 80 of slots into proper parallel coincidence and consequently draw the plates into proper longitudinal alignment. As already described that portion of the angle-bar running along the side edge of each of the plates is preferably provided with only one fastening, but the arrangement of these fastenings is such for the respective plates that there are always two fastenings for connecting together the abutting angle-bars of adjacent plates, one fastening being on one angle-bar and the other on the bar adjacent, arranged to pass through the respective sets of slots in these bars and work in opposite directions. After the passage of the jaws 85 13 through the two sets of slots in abutting angle-bars on the two sides of adjacent plates and the jaws have been turned to engage the inner ends 14 of the respective sets 90 of slots by which the plates are centered and brought into proper alignment both of projection and of extension, then the jaws are drawn in to engage the angle-bars binding them securely together and in which position they are held by the jaws until released 95 according to the operation of the fastenings 100 as above explained.

The forms are usually constructed by assembling the units or plates to form two adjacent walls between which the cement is poured or laid. It is necessary of course that these walls should be connected and some provision be made also for the adjustable connection of the walls to provide for the molding of concrete structures of different thicknesses. It is also necessary that the means for connecting the adjacent walls should be capable of being removed after the concrete structure has become dried. Difficulty has sometimes been encountered in the means employed for this purpose inasmuch as the removal of the connections has tended to break or splinter the concrete marring its surface at the point where the means of connection is removed. I have accordingly provided not only means of connection for effecting a proper adjustable 110 retention of adjacent walls of the form by which it may mold structures of different thicknesses, but I have also pro-

vided means of connection which can be removed from the dried structure without injuring it in any way and possessing also other advantages as will be explained.

5 By reference to Fig. 6 it will be observed that 27 and 28 represent, respectively, adjacent spaced walls made by the assembling of units or plates as above described. Between these walls for spacing the same is 10 placed a series of what may be termed separators 29. These separators are made of different lengths depending upon the required degree of separation of the walls and consequent thickness of the formed concrete 15 structure. The separators are made of concrete or of the same material of which the concrete structure is made and are preferably angularly formed as shown in order that they may become embedded and wedged 20 into the concrete structure when dried to eliminate any possibility of their endwise displacement, the intention being that the separators shall be left in the concrete structure and become as it were an integral 25 part thereof. Each of the separators has an opening or hole extending longitudinally through it. I prefer that such number of separators be employed that there shall be a separator between opposite spaced sets of 30 units or plates of those forming the respective walls. Accordingly each plate is provided with a hole or opening in it which will be in alignment with the hole or opening through the separator, the plates in the 35 adjacent walls accordingly having such precise order of arrangement that the holes preformed therein will be in alignment with one another and with the holes through the separators.

40 Extending through the holes in the respective plates and also through the openings in the space blocks, arranged in alignment with these holes, are a series of connecting rods 30, which act to hold the walls 45 in fixed position as follows:—Each of these rods is of considerable length; in fact, of such length that when the walls are most widely spaced from one another, according to the range of spaced adjustment provided 50 for, the ends of the rods will project beyond the outer sides of the adjacent plates or walls which they connect. The rod is notched for some considerable distance away from each of its respective ends providing a series of teeth 31. Each of these teeth is provided with an inclined edge 32. Fixed to each plate just adjacent to the opening therein through which the rod 30 extends is a fastening 33. Each of these 55 fastenings has a base plate 34 fixed to the exterior surface of the plate. Pivotal secured to this plate is a lever 35 having an operating arm 36 and a working arm or head 37. This working head of the lever 60 is in the nature of a cam having an inclined outer edge 38 which, when the lever is turned, is adapted to engage the edges 32 of any one of the teeth 31 depending upon the spaced adjustment of the two walls. The cam fastenings upon the separate plates 70 or walls are reversely arranged and accordingly draw against the teeth of the connecting bar in reverse directions and with the effect that as the teeth at opposite ends or parts of the bar resist the action of the cams 75 the resultant action is such as to press the plates to which the cams are secured hard against the ends of the separators, thereby holding the respective walls securely in place. After the concrete structure has become dried the connecting rods may be taken out simply by reversing the levers 35 when the cams are withdrawn from engagement with the teeth of the rod leaving the separators in the molded structure, and in 80 this connection it is especially to be observed that by reason of the initial formation of the separators, which ultimately form a part of the complete concrete structure, and the fact that the rods 30 pass loosely there- 85 through, the removal of the rods is obtained without injury to the structure. There will of course be an opening left through each of the separators. These openings, however, can be filled or plugged as is well 90 known to those skilled in the art. The openings, however, before filling provide a very convenient means by which a platform, or scaffolding may be secured to the molded structure, or wooden plugs may be inserted 95 in the holes on the inner side of the structure to which furring strips or finish may be attached. In this connection it may be observed that the separators are so retained that they may have any desired pre- 100 arrangement; or such pre-arrangement as to enable them to be used as bases to which furring strips or the like may be conveniently attached.

Having thus fully described my invention, I claim and desire to secure by Letters Patent of the United States:—

1. In a form for concrete structures, the combination with a plurality of assembled plates, of devices arranged on oppositely 110 acting pairs for drawing said plates into aligned position longitudinally and for securing the same together in said position.
2. In a form for concrete structures, the combination with a plurality of assembled 115 plates, of means for drawing said plates into aligned position both transversely and longitudinally and for securing the same in said position.
3. In a form for concrete structures, the 120 combination with a plurality of assembled plates provided with flanges on their backs adjacent the edges thereof, said flanges having longitudinally extending slots cut there- 125 in, of means cooperating with said slots 130

for drawing said plates into alined position longitudinally and for clamping together the abutting flanges of adjacent plates.

4. In a form for concrete structures, the combination with a plurality of assembled plates provided with flanges having longitudinally extending slots, of devices for drawing said plates into alined position longitudinally and for securing the same to-

gether in said position, said devices co-¹⁰ operating with the ends of said slots and being arranged in oppositely operating pairs.
